THROTTLE VALVE MECHANISM

Roy O. Allen, Athens, Pa., assignor to Ingersoll-Rand Company, New York, N. Y., a corporation of New Jersey

Application August 28, 1942, Serial No. 456,516

3 Claims. (Cl. 277—20)

This invention relates to fluid actuated tools, and more particularly to a throttle valve mechanism for controlling the supply of pressure fluid to such tools.

It is an object of the present invention to provide a throttle valve mechanism that requires only a small amount of space for its accommodation in a tool to which it may be applied and which may be conveniently operated to supply pressure fluid in successive order to different parts of the tool and at the same time to maintain adequate seals in the throttle valve mechanism in order to prevent the wastage of power medium.

Other objects will be in part obvious and in part pointed out hereinafter.

In the drawing accompanying this specification and in which similar reference numerals refer to similar parts,

Figure 1 is a longitudinal view, partly broken away, of a fluid actuated tool equipped with throttle valve mechanism constructed in accordance with the practice of the invention, and

Figure 2 is a transverse view taken through Figure 1 on the line 2—2.

Referring more particularly to the drawing, the tool embodying the invention is designated, in general, by 20 and is shown as being in the form of a riveting machine of a known type comprising a cylinder 21 having a chamber 22 for the accommodation of a power unit 23 of the fluid actuated percussive type which may normally be held in the rearmost position shown in Figure 1 of the drawing by a spring (not shown) in the front end of the cylinder 21.

As is customary in tools of this type, the power unit is slidable longitudinally of the chamber 22 and is in itself a complete unit having a hammer piston (not shown) and a suitable valve (not shown) for effecting the distribution of pressure fluid to actuate such hammer piston. The power unit 23, in the present instance, is intended to actuate a rivet set 24 for upsetting a rivet 25 in work pieces 26. The head of the rivet rests in a recessed block 27 carried by a yoke 28 and the yoke is attached to the cylinder 21 by bolts 29.

A closure is provided for the rearward end of the cylinder 21 in the form of a back head 30 secured to the cylinder by bolts 31, as indicated in Figure 2 of the drawing. The back head 30 also has a longitudinally extending chamber 32 to accommodate a plunger 33 that seats at its front end against the rearward end of the power unit 23. These ends of the plunger and of the power unit constitute, respectively, pressure surfaces 34 and 35 against which pressure fluid acts, in the first instance, for moving the power unit forwardly in the cylinder 21 to the operative position on the work and, in the second case, to press the power unit firmly against the rivet in accordance with the upsetting thereof as well as to supply pressure fluid to the power unit for driving its percussive element. Such pressure fluid is conveyed into the power unit by a passage, or

10 passages, 36 that is in constant communication with the rearward end of the chamber 22.

The back head 30 also constitutes a housing for the throttle valve mechanism forming the subject matter of this specification and is accordingly provided with a transverse bore 37 that extends entirely through the back head and is threaded at one end, as at 38, for the accommodation of a sealing member 39.

Within the bore 37 is a plug 40 that may be secured in assembled position in any well known manner and has an axial bore to form a valve chamber 41. The plug 40 preferably projects a slight distance from the open end of the bore 37 and is spaced from the sealing member 39, 20 with it cooperates to define a supply chamber 42 in the bore 37 for pressure fluid. The pressure fluid passes to the supply chamber 42 through a passage 43 in the back head and the outer end of the passage 43 is threaded as indicated at 44 for connection with a conduit (not shown) leading from a source of pressure fluid supply.

All the pressure fluid supplied to the various portions of the riveting tool is taken from the supply chamber 42 and the plug 40 is accordingly 30 provided with a passage 45 that opens at one end into the valve chamber 41, at a point near the supply chamber 42, and communicates at its other end with a longitudinally extending groove 46 in the periphery of the plug 40. The groove 46 opens into an annular groove 47, also in the periphery of the plug 40, and in the back head 30 is a passage 48 to afford communication between the annular groove 47 and the rearward end of the chamber 22.

The back head 30 is further provided with a second passage 49 that leads from the rearward end of the chamber 32 and communicates with a passage 50, in the plug 40, opening into the innermost end of the valve chamber 41.

Communication between the supply chamber 42 and the passage 45 is controlled by a throttle valve 51 of the poppet type, the head 52 of which cooperates with a seating surface 53 at the juncture of the valve chamber 41 and the supply chamber 42 for cutting off the flow of pressure

fluid from the supply chamber to the passage 45 and associated channels. The stem 54 of the valve 51 is slideable freely within the valve chamber 41 and in its periphery is an annular groove 55 to convey the pressure fluid from the supply chamber 42 to the passage 45 in the unseated position of the valve 51.

The valve 51 is hollow throughout its length having a bore 56 and in it is arranged a second valve 57, also of the poppet type, for controlling the flow of pressure fluid from the supply chamber 42 to the passage 50. The head 58 of the valve 57 seats against a tapered seating surface 59 on the valve 51 at the end of the bore 56 and the stem 60 is of such length that its free end projects from the end of the stem 54.

In the periphery of the stem 60, adjacent the head 58, is an annular groove 61 into which pressure fluid flows from the supply chamber 42 in the unseated position of the valve 57, and a passage 62 in the stem 60 conveys such pressure fluid from the groove 61 to a second annular groove 63 intermediate the ends of the stem 60. A passage 64 in the stem 54 affords communication between the annular groove 63 and the innermost end of the valve chamber 41. The annular groove 63 is of such length that it will remain in registry with the passage 64 in all the positions to which the valve 57 may be moved relatively to the valve 51.

Preferably a port 65 is formed in the valve stem 54 to afford communication between the grooves 55 and 61 in the closed positions of the throttle valves 51 and 57 and said valves are respectively held against their seats by springs 66 and 67 interposed between the valves and the sealing member 39.

In the form of the invention shown, the valves 51 and 57 are lifted from their seats to admit pressure fluid to the chambers 32 and 22 by a common actuating means that acts to unseat the valves in successive order. The actuating means is manipulated by manual force and is shown as comprising a rod 68 rotatable in lugs 69 on the cylinder 21 and in a bore 70 in the back head 30. The rod 68 is provided with a lever 71 whereby the said rod may be rotated and the lever 71 is located between the lugs 69 and may be secured fixedly to the rod in any well known manner.

On the end of the rod 68 projecting rearwardly from the bore 70 is a valve lifter 72 that may be suitably keyed to the rod and has a wing portion 73 to oscillate through the axes of the throttle valves accordingly as the rod 68 is actuated by means of the lever 71. The movement of the valve lifter is transmitted to the valves by a push rod 74 arranged slideably in a bore 75 in the plug 40 and axially of the throttle valves.

The inner end of the push rod 74 lies within the valve chamber 41 and has a head 76 to engage the end surface of the valve chamber for retaining the push rod 74 in the plug 40. The head 76 is at all times in position to engage the end of the valve stem 60 but is of less thickness than the space normally existing between the end surfaces of the valve chamber and the valve stem 60 so that the valve 57 may rest firmly on its seat without hindrance by the push rod.

Preferably the push rod 74 is provided with a passage 77 that communicates at its inner end with the adjacent portion of the valve chamber 41 and has a laterally extending branch 78 which is so located that it will be in communication with the atmosphere when both valves are seated but will be blanked-off by the wall of the bore

75 during the initial unseating movement of the valve 57.

The operation of the device is as follows: Whenever it is intended to upset a rivet 25 the valve actuator, including the valve lifter 72, is rocked inwardly towards the cylinder 21. During the initial movement of the valve lifter the push rod 74 will first unseat the valve 57. Pressure fluid will then flow from the supply chamber 42 through the channels in the valve stem 60 and the passage 64 into the inner end of the valve chamber 41, thence through the passages 50-49 into the chamber 32 and, acting against the pressure surface 34, will move the plunger and the power unit 23 forwardly in the cylinder 21 to place the rivet set 24 into contact with the rivet 25. During that portion of the opening movement of the valve 57 required to move the groove 61 out of registry with the port 65 a small amount of pressure fluid will also flow through the passage 45 and the associated channels into the rearward end of the chamber 22. The amount of pressure fluid thus admitted into the chamber 22 is, however, of insufficient volume to afford material assistance in moving the power unit forwardly or to set its distributing and percussive elements in operation.

Upon continued movement of the valve lifter 72 in the direction described the push rod 74 will contact the inner end of the valve stem 54 and the throttle valve 51 will be moved off of its seat. Pressure fluid will then flow through the annular groove 55, the passage 45, the grooves 46 and 47 and through the passage 48 into the rearward end of the chamber 22 to act against the pressure surface 35. The pressure fluid thus admitted into the chamber 22 will assist in pressing the power unit forwardly toward the work and at the same time a portion of such pressure fluid flows through the ports 36 into the power unit for distribution to actuate the hammer piston.

After the rivet 25 has been completely upset the lever 71 is released and the springs 66 and 67 will then return the valves 51 and 57 to their seats to cut-off the chambers 32 and 22 from the supply chamber 42. The pressure fluid in the chamber 22 will then pass through the distributing and percussive elements of the power unit to the atmosphere and such pressure fluid as may exist in the chamber 32 will return through the passages 49 and 50 into the inner end of the valve chamber 41, whence it escapes through the passages in the push rod 74 and through the passage 64, the channels in the valve stem 60, the port 65 and the connecting passages to the chamber 22 to pass through the power unit to the atmosphere.

In practice, the present invention has been found to be particularly well suited for use in power tools in which it is desirable that the weight of the entire structure be maintained at a minimum and in which it is required to valve pressure fluid in successive order to different portions of the tool. The throttle valve structure, as may be readily observed, requires only a small amount of space and at the same time all the ports and passages in the throttle valves and those which the throttle valves control may be conveniently located in such wise that they will be adequately sealed against leakage in the various positions that the throttle valves may occupy.

I claim:

1. A throttle valve mechanism, comprising a

casing having valve and pressure fluid supply chambers and a plurality of passages opening into the valve chamber, a pair of throttle valves for controlling the flow of pressure fluid from the supply chamber to the passages, and both throttle valves having channels registering with each other for conveying pressure fluid to one of the passages, and a common means for actuating the throttle valves successively.

2. A throttle valve mechanism, comprising a casing having valve and pressure fluid supply chambers and passages opening into the valve chamber, a pair of reciprocatory throttle valves in the valve chamber for controlling the flow of pressure fluid to the passages, there being channels in both throttle valves to convey pressure fluid from the supply chamber to one of the passages, a seat on one valve for the other valve, and a common means for actuating the throttle valves successively.

3. A throttle valve mechanism, comprising a

5 casing having valve and pressure fluid supply chambers and passages opening into the valve chamber, a pair of reciprocatory throttle valves in the valve chamber for controlling the flow of pressure fluid to the passages and one throttle valve being arranged slidably in the other, there being channels in both valves for conveying pressure fluid from the supply chamber to one of the passages, a seat on the casing for the outermost throttle valve, a seat on the outermost throttle valve for the other throttle valve, and manually operated means for actuating the throttle valves movable in one direction to first unseat the innermost throttle valve to communicate the channels with the supply chamber for supplying pressure fluid to one passage and upon further movement in such direction to next unseat the other throttle valve for valving pressure fluid from the supply chamber to another passage.
